UNITED STATES PATENT OFFICE.

JOHN H. BROWN, OF NEW YORK, N. Y., ASSIGNOR TO THE BROWN STANDARD FIRE ARMS COMPANY, OF SAME PLACE.

GUN-BARREL.

SPECIFICATION forming part of Letters Patent No. 290,738, dated December 25, 1883.

Application filed May 22, 1883. (No model.)

To all whom it may concern:

Be it known that I, JOHN H. BROWN, of New York, in the county and State of New York, have invented a certain new and useful Improvement in Fire-Arms, of which the following is a specification.

An ordinary rifle-barrel has at the breech a chamber for the reception of a cartridge, and this chamber extends slightly forward of the shell of the cartridge, leaving a space beyond the shell into which the bullet of the cartridge will upset when the cartridge is fired. The objections to the upsetting of the bullet into this space are numerous and well known. The object of my improvement is to avoid this space.

To this end the improvement consists in a rifle-barrel having near the breech and just in rear of the rifling a forwardly-tapering internal portion, and having at the breech a differently tapering or cylindric portion, and adapted for use in combination with a cartridge having a shell which has an external forward taper corresponding to the forwardly-tapering portion of the barrel that is just in rear of the rifling, and which is of such length that at its forward end it will extend into and fit in the said forwardly-tapering portion that is just in rear of the rifling, and at the rear end will fit in said differently tapering or cylindric portion of the barrel. When such cartridge is fired, its shell will be expanded behind the said forwardly-tapering portion of the barrel, so as to be prevented from being carried forward with the bullet, and the upsetting of the bullet to any objectionable extent is avoided.

The accompanying drawing is a longitudinal section of a portion of a rifle-barrel, and a longitudinal section of a cartridge embodying my improvement.

A designates the rear end of a rifle-barrel. It has a chamber which is adapted to receive a cartridge, B. This chamber consists of a forwardly-tapering portion, a, which is forward of the breech of the barrel, and just in rear of the rifling b, and a differently tapering or cylindric portion, c, extending from the forwardly-tapering portion, a, to the breech. What I mean by a "differently tapering" portion, c, is a portion which tapers forwardly,

but at such a different angle from the angle of the tapering portion a in front of it that a shoulder, d, will be formed at its junction with the tapering portion a. Obviously, if the portion c were made cylindric a shoulder would be formed at its junction with the tapering portion a. It will not be so desirable to make the portion c cylindric as tapering, because when made tapering the cartridge-shells can be more easily extracted.

The shell of the cartridge B is made to taper externally toward the forward end, and its angle of taper will be approximately the same as the angle of taper of the portion a of the barrel; hence when in place its exterior and the portion a of the barrel will be coincident. This shell is of such length that the entire portion which surrounds the bullet extends into the tapering portion a of the barrel, and hence forward of the shoulder d. Owing to the manner in which cartridge-shells are ordinarily made, it will be most convenient to make the interior of my cartridge-shell parallel with the exterior. The forward portion, e, of the interior of the shell is, however, made cylindric, to conform to the cylindric portion of the bullet, and owing to this formation of the shell the interior and exterior of the shell converge at the forward end to a fine edge, which is about equal in thickness to the difference between a radius of the adjacent part of the tapering portion a of the barrel, and a radius of the rifled portion of the barrel. It will be obvious, therefore, that the space between the cartridge-shell and the rifling is not a short abruptly tapering space, as usual, but is a long gradually-tapering portion; and hence it will be perceived that the upsetting of the bullet will be extended over a greater length of its surface, and will be very gradual, so as not to be seriously objectionable. The diameter of the rear portion of the cartridge-shell and the diameter of the portion c at the rear of the barrel are about the same, so that the cartridge-shell will fit snugly in the barrel at the breech or rear end. I desire to remark that the difference in size between the rear end of the forwardly-tapering portion and the forward end of the differently tapering or cylindric portion c is not to be so great as to interfere with the cartridge-shell fitting snugly in the barrel at the rear end.

dric portion is so slight that there is formed at the junction a shoulder so small that on the firing of a cartridge the cartridge-shell will be expanded behind without bursting. If the 5 shoulder were so large as to endanger the bursting of the shell, the result sought to be accomplished might be frustrated, because the forward end of the shell might be cut off from the main portion, so that it could not be pulled 10 out with the main portion.

The cartridge-shell may be made of sheet metal, as usual, and may be drawn out or otherwise treated to produce the internally-cylindric portion *e* at the forward end. When 15 the cartridge is fired, its shell will be expanded into the portion *e* behind the shoulder *d*, and thus it will be prevented from being carried through the barrel.

What I claim as my invention, and desire to 20 secure by Letters Patent, is—

1. A rifle-barrel having near the breech and just in rear of the rifling a forwardly-tapering internal portion, and having at the breech a differently tapering or cylindric portion, and 25 adapted for use in combination with a cartridge having a shell which has an external

forward taper corresponding to the forwardly-tapering portion of the barrel that is just in rear of the rifling, and which is of such length that at its forward end it will extend into and 30 fit in the said forwardly-tapering portion that is just in rear of the rifling, and at the rear end will fit in said differently tapering or cylindric portion of the barrel, substantially as specified.

2. The combination, with a rifle-barrel having near the breech and just in rear of the rifling a forwardly-tapering internal portion, and having at the breech a differently tapering or cylindric portion, of a cartridge having 40 a shell which tapers externally toward the forward end, which at the forward end is internally cylindric, and which fits at the forward end in the said forwardly-tapering portion of the barrel that is just in rear of the rifling, 45 and which fits at the rear end in the rear end of the said differently tapering or cylindric portion of the barrel, substantially as specified.

JOHN H. BROWN.
